TELEPHONE HANDSET ATTACHMENT

Alvin R. Vögel, Los Angeles, Calif.

Application October 23, 1950, Serial No. 191,541

9 Claims. (Cl. 179—188)

1

This invention relates to an attachment for use on a hand telephone, the attachment being selectively adjustable so as to more accurately direct voice waves into the transmitter and to selectively prevent the passage of sound waves into the transmitter, thereby permitting the user of the telephone to listen to the receiver and upon desired occasion to talk to others without having the user's conversation picked up by the transmitter.

Heretofore numerous devices have been disclosed, said devices being termed "silencers," the primary purposes of the devices being to permit the user of a telephone to speak therewithout being overheard by others in his immediate vicinity. In addition, certain extraneous devices were proposed for the purpose of shielding or silencing the transmitter so as to prevent sound from passing into the transmitter. One such device is illustrated in Patent No. 2,484,450.

The present invention is directed to a simple, lightweight, efficient device capable of being readily attached to the mouthpiece or transmitter of a usual hand-type telephone, this device having a dual function in that it more accurately directs the voice waves into the transmitter, thereby permitting the transmission of low amplitude sounds and privacy, and in addition the device is selectively adjustable so as to prevent passage of sound waves into the transmitter, thereby allowing the user of the telephone to listen to the receiver and talk to others without having the user's conversation with such others picked up by the transmitter.

The constructions embodying the present invention and described hereinafter permit the use of the hand phone in the normal manner. The invention does not involve the use of extraneous objects or devices which are normally misplaced, since they are not connected to the hand phone. The present device does not necessitate the use of greater desk space for the phone. The device is simply attached without the use of tools.

Generally stated the device of the present invention, in its simplest embodiment, consists of a hollow, virtually semi-spherical directional member resembling a scoop and provided with a skirt capable of resiliently grasping the mouthpiece. Part of this semi-spherical member is in the form of a scoop-like lune, or fixed hood tending to guide the voice through an aperture in such member into the transmitter of the telephone. Pivotally mounted upon this virtually semi-spherical scoop-like member is a hollow, movable hood for selective, slidable movement over the fixed hood

of the scoop-like member and over the port therein, thereby permitting selective closure of the port. In a modification of the present invention the selective movement of the hood is accomplished by means of a lever cooperating with the handle of the hand phone, whereby manipulation of the lever with a finger while holding the phone in the position of use, selectively opens and closes the phone by imparting movement to the hood.

In the modified form of the invention just referred to, the lever is preferably spring-biased so that the movable hood is continually urged into its closed position. During normal use of the telephone, the lever is digitally held in position adjacent the handle against the force of the spring, the movable hood then being open. If during the conversation the user wishes the hood to be closed, thereby effectively silencing the transmitter, he may release his fingers from the lever, thus allowing the lever to move outwardly away from the handle and permitting the spring to close the hood. If it is desired that the hood remain open throughout a conversation, the lever may be pressed firmly against the handle of the telephone handset intermediate the receiver and transmitter, and means are provided on the lever for engaging the longitudinal grooves normally formed in the handle portion of the handset. To restore the device to selective operation thereafter, it is only necessary to release the lever from its engagement with the indentations. The lever is so formed as not to interfere with the handset when the telephone is not in use and is resting upon the support conventionally provided.

An object of this invention is, therefore, to provide a novel attachment for selectively silencing the transmitter of a telephone.

Another object of the invention is to disclose such a device including means for channeling desired sound waves into the transmitter of the telephone and simultaneously restricting the passage of undesired sound waves therewith.

A further object is to disclose such a device which may be attached to a conventional telephone handset without increasing the amount of desk space occupied by the instrument.

A still further object is to provide such a device which is easily attachable to a telephone handset or detachable therefrom without the use of tools.

Another object is to disclose such a device which is simple and economical in manufacturing and yet reliable and efficient in use.

These and allied objects and purposes of the invention will become clear from a study of the

following description thereof taken in connection with the accompanying drawing of illustrative embodiments.

In the drawing:

Fig. 1 is a side elevational view of a conventional telephone handset showing one form of the present invention attached to the transmitter.

Fig. 2 is a sectional view taken on line II-II of Fig. 1.

Fig. 3 is a fragmentary view similar to Fig. 1 except that the movable hood is in closed position.

Fig. 4 is a fragmentary view of a conventional telephone handset with a modified form of the present invention attached thereto.

Fig. 5 is a sectional view taken on line V-V of Fig. 4.

Fig. 6 is a fragmentary view of the device shown in Fig. 4, the movable hood being in closed position.

Fig. 7 is a sectional view taken on line VII-VII of Fig. 4.

Fig. 8 is a sectional view taken on line VIII-VIII of Fig. 4.

Fig. 9 is an enlarged fragmentary sectional view of my device, taken on line IX-IX of Fig. 1.

Referring now in detail to Fig. 1, a conventional telephone handset is indicated generally at 10 and includes receiver 11 and transmitter 12 joined by an integrally formed handle 13. Transmitter 12 includes a circular cap or mouthpiece 16 which is connectable by threaded engagement with the body portion of transmitter 12. A member indicated generally at 18 is provided with a circular skirt 19 arranged to encircle and frictionally grasp the cap 16. The circumference of mouthpiece 16 tapers very slightly, as indicated at 15, and the skirt 19 is preferably made of material having a small resiliency, whereby skirt 19 grasps mouthpiece 16 securely to prevent accidental dislodgement of the device from the mouthpiece, at the same time permitting manual removal of the attachment when desired.

The member 18 also includes a fixed hood 21 resembling a scoop and extending across the lower portion of transmitter 12 and spaced therefrom, the major portion of member 18 being open and constituting a port giving external sound waves access to transmitter 12. Member 18 is also provided with a pair of diametrically opposite ears or lugs 22 and 23, and the ears carry outwardly projecting pivot pins 24 and 25 respectively. A movable hood, indicated generally at 27, includes holes 24' and 25' in which pivot pins 24 and 25 are respectively journaled. Fixed hood 21 and movable hood 27 are each preferably formed as portions of the surface of spheres, fixed hood 21 having an outer radius very slightly smaller than the inner radius of movable hood 27. Movable hood 27 includes at its upper end a projecting ear or boss 28.

It will be seen by reference to Figs. 1, 2 and 3 that movable hood 27 may be selectively disposed in either of two positions. When disposed as shown in Fig. 1, access of external sound waves to the transmitter 12 is substantially unrestricted, whereas the position of movable hood 27 shown in Fig. 3 effectively silences the transmitter 12 since sound waves are prevented from impinging the operative elements (not shown) of transmitter 12. The projecting ear or boss 28 is easily engaged with the tip of a finger for

flipping movable hood 27 into either its open or closed position. Moreover, it will be noted by reference to Fig. 1 that sound waves originating from the position of the mouth of the user (schematically indicated at 31) will be effectively channeled into transmitter 12, the fixed hood 21 and movable hood 27 exhibiting their concave surfaces to sound waves thus propagated. On the other hand, it will be noted that sound waves originating from sources removed from point 31 will in greater or lesser degree impinge the outer convex surface of movable hood 27 and will be thereby deflected away from transmitter 12. Thus, when movable hood 27 is in its open position as in Fig. 1, the volume of the user's voice may be appreciably lower than would otherwise be necessary to achieve satisfactory electrical transmission of his voice, and at the same time the effect of external sources of sound other than the user's voice is substantially diminished. With the movable hood 27 in its closed position, as in Fig. 3, a continuous convex substantially hemispherical surface is presented to all external sound, thus virtually eliminating the entry of any sound waves into transmitter 12.

In order to insure a snug fit between mouthpiece 16 and circular skirt 19 of directional member 18, I preferably provide on said skirt a plurality of circumferentially spaced, inwardly projecting ears or fins 20. These ears or fins are made of material having somewhat greater resiliency than the relatively less resilient material used in making skirt 19, and are permanently fixed to said skirt as by being integrally molded therewith or by other suitable means. Ears 20 are preferably provided with tapered sides 20', the inner end of each ear 20 being somewhat narrower than the base thereof as appears in Fig. 9. Circular skirt is thereby retained in correct position relative to mouthpiece 16, and may be removed therefrom easily and quickly when desired, by reason of the resiliency of ears 20.

Although I have shown and described in detail a movable hood 27 which is pivotable relative to the stationary directional member 18, it will be immediately evident that said movable hood can be made to be rotatable relative to directional member 18. Thus the outer circumferential wall of circular skirt 19 may be provided with a circumferential groove extending therearound, and movable hood 27, instead of being pivotally connected to the directional member 18, may be provided with a flange partially or completely encircling circular skirt 19, said flange including an inwardly extending continuous lip or a plurality of spaced lugs slidably engaging the groove in the circular skirt.

For added convenience in use, I may provide additional elements shown in Figs. 4, 5, 6, 7 and 8. In common with the embodiment of my invention previously described, the modified device includes directional element 18, skirt 19, fixed hood 21 and movable hood 27. Directional member 18 in this embodiment includes arms 36 and 37 extending appreciably farther alongside transmitter 12 than ears 22 and 23 previously described. Arms 36 and 37 are provided with holes 38' and 39' in which are journaled pivot pins 38 and 39 respectively. An operating lever indicated generally at 41 includes a pair of arms 42 and 43 extending substantially parallel to the handle 13 of handset 10 and lying on either side of said handle. Arms 42 and 43 terminate at

their upper ends in enlarged portions 44 and 45, the enlarged portions being joined together by an integral bridge member 46. Arms 42 and 43 include at their lower ends holes for pivotally engaging pivot pins 38 and 39 respectively and are further provided with segments of spur gears 52 and 53. Movable hood 27 is provided with a pair of toothed hubs 54 and 55, said hubs meshing with the respective segments of gears 52 and 53. It can now be seen that movement of operating lever 41 from the position shown in Fig. 4 to the position shown in Fig. 6 will cause movable hood 27 to be moved from its open position to its closed position.

I preferably include a pair of spring members 58 and 59 associated with pivot pins 38 and 39 respectively arranged to urge lever 41 and movable hood 27 into the position shown in Fig. 6. Arms 42 and 43 include integrally formed inwardly extending flanges or lugs 62 and 63 respectively. One end of spring members 58 and 59 bears against the respective flanges 62 and 63 and the other end of spring members 58 and 59 engages the inner end of arms 36 and 37 respectively. The spring members are tensioned to urge lever 41 in a clockwise direction as viewed in Figs. 4 and 6.

In normal use of the attachment shown in Fig. 4, the user's fingers encircle handle 13, and releasing the one or two fingers contacting bridge member 46 permits spring members 58 and 59 to move the parts to the position of Fig. 6, as above set forth. It may on occasion be desired to retain the parts in the position of Fig. 4 even when the fingers are released, and to accomplish this, means are provided for selectively retaining lever 41 adjacent handle 13. The conventional handset 10 is provided with a pair of longitudinal grooves or channels 72 and 73 extending adjacent the inner surface of handle 13. Grooves 72 and 73 are normally U-shaped in section, as best appears in Figs. 7 and 8, and I provide complementary ribs 74 and 75 on the inner surfaces of enlarged portions 44 and 45 of lever 41 for engaging the respective grooves 72 and 73. Normally ribs 74 and 75 do not engage the grooves, but the slight resiliency of the enlarged portions 44 and 45 permits a small force applied to bridge member 46 to move the parts into the position of Fig. 7. A small force in the opposite direction applied against lever 41 moves the lever rightwardly as viewed in Figs. 4 and 7 and restores the lever to normal digital operation.

It will be noted that the pivot points of movable hood 27 are set inwardly from the plane of the face of cap or mouthpiece 16, said pivot points being located at poles of a great circle of a sphere of which movable hood 27 is a portion. Furthermore, directional member 18 is resiliently attached to mouthpiece 16 along a small circle of the sphere of which fixed hood 21 is a portion. Thus the mouthpiece is completely covered when the parts are in the position of Fig. 3 or Fig. 6, thereby effectively blocking external sound waves from access to transmitter 12 and silencing the instrument.

Thus I have provided a reliable, simple attachment for telephone handsets having no interference with the electrical connections thereof. When the movable hood is open, the user's voice is more effectively channeled into the transmitter and unwanted external noises are diminished. With the movable hood closed, the transmitter is effectively silenced. The slight

resiliency of the material of which the attachment is made permits the device to be manually attached to or detached from an instrument.

I prefer to form the several elements of the device of an organic condensation or polymerization product of thermoplastic or thermo-setting characteristics having suitable strength in molded or cast form. I may include plasticizers, finely divided fillers, reinforcing agents, pigmenting materials, etc. Phenol-formaldehyde resins, polyvinyl compounds and styrene resins are examples of suitable materials.

It will be immediately evident to those skilled in the art that modifications and changes may be made from the specific forms shown and described hereinabove without departing from the spirit of the invention. All such modifications and changes are intended to be included in the scope of the appended claims.

20 I claim:

1. An attachment for hand telephones comprising: a hollow, virtually semi-spherical scoop-like member including a lune, a port adjacent thereto and provided with a skirt terminating in a large part in an edge which is in the plane of a small circle of a sphere, said skirt being arranged to slidably fit and resiliently grasp the mouthpiece ring of a telephone; and a hollow movable hood in the form of a lune, said hollow hood being pivotally connected to the scoop-like member at points corresponding to the poles of a great circle for selective slidable movement over said member and over the port therein to selectively close the port.

35 2. An attachment of the character stated in claim 1 wherein the outer radius of the semi-spherical direction member is slightly smaller than the inner radius of said movable hood, and said lune and movable hood are concentric.

40 3. An attachment for a telephone handset having a transmitter, a receiver and a handle joining said transmitter and receiver comprising: a scoop-like member frictionally engageable with said transmitter, including a fixed hood extending across a portion of said transmitter and spaced therefrom and a port adjacent said fixed hood and extending across the remaining portion of the transmitter, said fixed hood constituting a portion of a sphere; a movable hood 50 overlying said fixed hood and constituting a portion of a sphere having a radius slightly greater than the radius of the first named sphere, said spheres having a common center; and a pivotal connection between said movable hood and said scoop-like member whereby said movable hood is enabled to swing across and close said port.

45 4. An attachment as stated in claim 3 including a lever rotatably carried by said scoop-like member at a point spaced from said pivotal connection and means for transmitting rotational motion of said lever to said movable hood.

50 5. An attachment of stated in claim 4 including a spring member urging said movable hood into closed position.

55 6. An attachment for a telephone handset having a transmitter, a receiver and a handle joining said transmitter and receiver comprising: a scoop-like member including a fixed hood attachable to said transmitter, said fixed hood having the shape of a spherical lune overlying a portion of said transmitter; a movable hood pivotally connected to said scoop-like member, said movable hood having the shape of a spherical lune of slightly larger radius than the first named 70 spherical lune, said spherical lunes being con-

centric; a lever pivotally carried by said scoop-like member having a pair of arms arranged to partially embrace and selectively grasp said handle; and means associating said lever and movable hood whereby movement of the lever causes rotation of said movable hood about its point of pivotal connection.

7. An attachment as stated in claim 6 wherein said arms include inwardly extending ribs selectively engageable with the handle of said handset. 10

8. An attachment as stated in claim 6 including a spring member carried by the point of pivotal connection between said lever and said scoop-like member arranged to urge said lever away from said handle.

9. An attachment for a telephone handset having a transmitter, a receiver and a handle joining said transmitter and receiver comprising: a scoop-like member frictionally engageable with said transmitter, including a fixed hood extending across a portion of said transmitter and 20

spaced therefrom and a port adjacent said fixed hood and extending across the remaining portion of the transmitter; and a second hood movably attached to said scoop-like member and arranged to be selectively positioned to either close said port or to be disposed in nesting relation with said fixed hood.
